UNITED STATES PATENT OFFICE.

ISAAC HIRSCH, OF CHICAGO, ILLINOIS.

DESIGN FOR A BREAD-PAN.

SPECIFICATION forming part of Design No. 27,722, dated October 12, 1897.

Application filed December 21, 1896. Serial No. 616,550. Term of patent 7 years.

To all whom it may concern:

Be it known that I, ISAAC HIRSCH, a citizen of the United States, residing at Chicago, in the county of Cook, State of Illinois, have 5 invented a certain new and useful Design for Bread-Pans, of which the following is a description.

My invention relates to a new and improved design for a bread-pan or the like and is illustrated in the accompanying drawings, wherein—

Figure 1 is a plan view of a bread-pan embodying my invention. Fig. 2 is a side elevation of a bread-pan embodying my invention.

Like letters refer to like parts throughout both figures.

As illustrated in the drawings, the pan consists of the cylindrical part A, provided with

centrally-located projecting parts A' B', which 20 extend around the pan. Said pan is provided with the centrally-disposed corrugations C, which extend part way of the length of the pan. The ends of the pan are provided with corrugations D at an angle to the corruga- 25 tions C.

The essential feature of my design is the pan with centrally-disposed corrugations extending around its middle portion and end corrugations at an angle with the centrally- 30 disposed corrugations.

I claim—

The design for a bread-pan as herein shown and described.

ISAAC HIRSCH.
